(57) **CLAIM**

The ornamental design for analyte-determining meter, as shown and described.

DESCRIPTION

FIG. 1 is a top perspective view of an analyte-determining meter.

FIG. 2 is a bottom perspective view of the analyte-determining meter.

FIG. 3 is a first side view of the analyte-determining meter.

FIG. 4 is a first end view of the analyte-determining meter.

FIG. 5 is a front plan view of the analyte-determining meter.

FIG. 6 is a second end view of the analyte-determining meter, which is opposite of the first end view of FIG. 4.

FIG. 7 is a back plan view of the analyte-determining meter, which is opposite of the front plan view of FIG. 5; and,

FIG. 8 is a second side view of the analyte-determining meter, which is opposite of the first side view of FIG. 3.

The portions of the drawings shown in broken lines represent environmental structure and form no part of the claimed design.
